(57) **CLAIM**

The ornamental design for a remote controlled docking assembly for media device, as shown and described.

DESCRIPTION

FIG. 1 is a perspective view of a remote controlled docking assembly for media device showing our new design;

FIG. 2 is a front elevation view thereof;

FIG. 3 is a rear elevation view thereof;

FIG. 4 is a left side elevation view thereof;

FIG. 5 is a top plan view thereof;

FIG. 6 is a bottom plan view thereof;

FIG. 7 is an alternate front elevation view thereof, showing a remote control in connection with the docking assembly; and,

FIG. 8 is right side view thereof.

The broken line showing of the plug elements and remote control are included for the purpose of illustrating environmental structure and forms no part of the claimed design.
